2 Claims. (Cl. 38—35)

1

This invention relates to garment and like presses of the kind comprising an ironing head or upper buck, hereinafter called the head, and a lower padded buck on which the work to be pressed is spread, with power operated means for effecting pressure between the head and the buck.

Garment presses of the kind indicated may be divided into two main types. In one type of press which is that in more general use the head is movable and is pressed downwardly to the fixed lower buck, the head being carried on a pivoted arm to which power is applied through toggle mechanism or other appropriate power transmission means from a fluid pressure piston and cylinder arrangement. The other main type of press may be termed the upward pressure type, as in such presses the head is fixed, and the buck is moved upwardly to press the garment or other work between it and the head.

In upward pressure type presses usually the lower buck is arranged to be swung in a horizontal plane from a loading position into a position in which it becomes associated with a ram or other pressing device which can then operate to force the buck upwardly, but there have been proposed upward pressure type presses in which the lower buck is carried by supporting means pivoting on a fixed horizontal axis or axes, the buck swinging from a forward loading and unloading position in front of the vertical plane containing the said axis or axes to a pressing position in or rearward of said vertical plane. In these proposed presses there is operatively associated with the buck support or carrier the piston of a fixedly mounted power cylinder, which effects both the swinging movement of the buck, to bring it from its loading position into pressing position, and the closing movement, and also applies and maintains the pressure of the lower buck against the fixed head.

The press according to the present invention is of the upward pressure type and also of the kind in which the means carrying the lower buck pivots about a fixedly located horizontal axis so that the buck swings from a loading position forwardly of the vertical plane containing the said axis to a pressing position rearwardly of said plane, and the object of the invention is to provide an improved press of this kind which shall be of simple construction and which, in addition to being safe to operate, shall be such that the weight of the lower buck will be counterbalanced or largely counterbalanced by the weight of the power applying device thereby rendering the press such that little effort is needed to swing the said buck from loading to pressing position, and vice

2

versa. A press according to the invention also is such that not only can the moving element of the power applying device be in constant operative association with the lower buck carrier or support means, but also such that said element can be directly and rigidly connected to said carrier; thus the lower buck carrier can be constituted by the piston rod of the power applying cylinder, thereby eliminating all linkage, sliding cross heads, or other power transmission means between the moving element of the power applying device and the carrier.

The press embodying the invention affords many advantages over presses of both the main types above referred to as at present constructed, amongst the advantages being a large reduction in the number of parts and considerable simplification of the piping arrangements as well as a reduction in the floor space occupied as compared with upward pressure presses of similar capacity in which the buck is swung in a horizontal plane from loading to pressing position and vice versa.

In a garment or like press according to this invention the power applying cylinder of the press is incorporated in the lower portion of the movable unit thereof and with or without an additional weight or weights is disposed in relation to the pivotal axis of the unit in such manner that the lower portion of the unit almost counterbalances the upper portion thereof which includes the lower buck.

In an embodiment of the invention the moving element of the power applying piston and cylinder arrangement is directly and rigidly connected to the lower buck carrying means. Further, the supply of fluid under pressure to the power applying cylinder to cause upward pressure of the buck against the head is effected as the buck unit reaches, and whilst it occupies, the pressing position, means being provided for exhausting pressure from said cylinder to release the press.

As the pivotal centre of the lower buck unit preferably is so disposed that the power applying cylinder alone or with an associated weight or weights almost counterbalances the buck, so that little energy is needed to move the unit from the loading to the pressing position and vice versa, it is convenient for the buck and power unit to be moved by hand to and from its position of rest, but if desired, the machine may incorporate provisions for moving the said unit by power.

Preferably the arc of movement of the lower buck is such that its loading and pressing positions are equidistantly spaced from the centre-line of the machine forwardly and rearwardly

thereof with the distribution of weight of the unit relative to its pivotal centre such that the buck portion of the unit slightly over-balances the cylinder portion and thus when moved into either the loading or pressing position will remain therein until action is taken to move it into its other position. With the parts disposed as just mentioned the head curves or slopes downwardly to its rear edge so that drainage of its hollow interior constituting its steam chamber is facilitated.

Advantageously, the machine incorporates means whereby as the buck reaches the pressing position power is applied automatically to move it upwardly and press the work against the head. The invention however is not limited in this respect as, if desired, the supply of power to the machine may be manually controlled, arrangements being included whereby such supply could be effected only when the buck is in the pressing position.

Any convenient form of releasing means for the press may be provided and when two machines are arranged to be used by a single operator, provisions may be included whereby the closing of one press will release the other and cause or permit the buck of such other press to be moved into loading position.

In the accompanying drawings:

Fig. 1 is a sectional elevation of a garment press according to one embodiment of the invention.

Fig. 2 is a view similar to Fig. 1 of a garment press according to another embodiment of the invention.

Fig. 3 illustrates in section and to a larger scale than Figs. 1 and 2, the pedal actuated press release valve and the control valve actuated automatically by the buck unit shown in each of those figures, with portions of the associated piping, and

Fig. 4 is a fragmentary view, partly sectional, of the means illustrated in Figs. 1 and 2 for guiding the buck unit in its movement from its loading position to its pressing position, and vice versa.

The presses illustrated in the drawings will now be described with reference to such drawings, and as the description proceeds, reference will be made to advantages arising from the inclusion of certain features of construction. In a press according to the embodiment of the invention shown in Fig. 1 the main frame or pedestal 1 of the machine has an arm or bracket 2 extending rearwardly and upwardly from it and cranked or turned forwardly to carry the fixed upper buck or head 3. Trunnioned at 4 in suitable bearings in the main frame or pedestal 1 is the head 5 of the power applying cylinder 6 of the press, such head having a relatively long bearing 7 for the rod 8 of a piston 9 reciprocable in the cylinder. In the construction shown a dished member constitutes both the cylinder proper and its base or end cover 10. The piston rod 8 extends upwardly from the cylinder 6 and through a guide slot in the top of the frame or pedestal 1, this slot extending in a direction from front to rear of the machine. Conveniently and as shown, the sides of the slot are fitted with removable, and thus renewable, wearing strips 11 forming the guides, and the piston rod 8 carries an appropriately surfaced member 12 adapted to work between the said guides.

Preferably and as shown, the piston rod 8 carries a work table 13, and the member 12 is constituted by the boss of this table which serves to mount the table on the piston rod. At its upper end the piston rod 8 carries the lower buck 14 of the machine which is padded and clothed or cov-

ered as usual. Below the lower buck 14 at a suitable distance therefrom the combined power cylinder and buck unit is provided with a handle 15 for swinging the buck, such handle conveniently being mounted on or adjacent the front edge of the work table 13 mounted on the piston rod. Suitable buffers or spring stops 16, 17 are carried by the frame or pedestal 1 against which the piston rod comes to rest in the loading and pressing positions of the buck, respectively, the rear buffer 17 being accurately positioned to ensure that when the unit is brought to rest thereagainst, the buck 14 will occupy the correct pressing position relative to the head 3. In the construction shown the boss 12 of the table 13 is rectangular in cross section, its front and rear faces contacting the buffers 16, 17 respectively, while its remaining two flat sides co-operate with the guide strips 11.

20 The machine includes piping (not shown) for conveying steam to the steam chamber in the head 3 and other piping 18 for conveying drainage from the said chamber, as well as piping 19, 20, 21 to carry compressed air from the supply to the pressing cylinder 6. Also included are the valve 22 controlling supply of compressed air to the cylinder 6 and a release valve 23, Fig. 3, means such as a treadle lever 24, fulcrumed at 25, Fig. 3, in the pedestal 1, being provided in a position convenient for actuation by an operator for operating such release valve 23, through the rod 26. As usual a silencer is mounted on the machine through which air exhausting from the power cylinder 6 passes to atmosphere. In addition, 30 there is provided at an appropriate distance from the front of the main frame or pedestal 1 and at a suitable height above ground, a guard rail 28, the purpose of which will be indicated later. Some description will also be given later of certain 35 constructional details conveniently employed in certain of the devices to which reference has already been made.

In working with a machine constructed according to the particular embodiment of the invention shown in Fig. 1, the operator as usual, spreads or arranges the garment or other article to be pressed on the lower buck 14, which, with a machine according to the invention will be in its forward or loading position. When the work has 40 been satisfactorily positioned on the buck 14, the operator will swing the buck unit into the pressing position shown in dotted lines. When the unit has nearly reached its pressing position, an appropriate portion thereof, as shown the piston rod 8, actuates the power supply valve 22 opening same to cause compressed air to pass to the cylinder 6. Thereupon, the piston 9 of the cylinder 6 moves upwardly and forces the buck 14 towards the head 3, pressing the garment between these parts as will be understood. After an appropriate interval, the operator actuates the release valve 23 and fluid pressure will be exhausted from the cylinder 6, the unit moving 50 downwardly to a limited extent. The operator 55 will then swing the unit into loading position and remove the pressed garment, reloading the machine and repeating the operations as will be appreciated without further description.

With the buck 14 in the loading position it lies 60 an appropriate distance forward of the front edge of the steam heated head 3 and thus there is no liability of the operator's hand or arm contacting the heated head when loading or unloading the machine. As usual in clothes presses the opposed 65 surfaces of the buck 14 and head 3 are convex

and concave respectively, and the curvature is such that a relatively small clearance only is needed between these parts during the swinging movement of the buck into and out of its pressing position. This small clearance, together with the projection of the guard rail 28 from the front of the machine, may be such as to so reduce the liability of the fingers of the operator being placed between the buck and the head that it may not be necessary to provide any form of so-called two-hand control such as is commonly employed for preventing the hands of the operator being caught between the pressing elements. Such controls, which are well known, require simultaneous action by both hands of the operator to close the press. However, a two-hand control may be provided, if desired, and/or the machine may be equipped with a guard or fence moved automatically into obstructive position in front of the pressing elements as the buck approaches its pressing position, and moved automatically out of obstructive position as the buck commences to move towards its unloading position.

If desired, means may be provided for heating the lower buck 14, such means conveniently consisting of a steam coil arranged in a suitably shaped grooving or channelling in the base plate or member of the buck, with suitable valve means for controlling the supply of steam to the coil, 29 being a portion of flexible tubing conveying exhaust steam and condensate from the buck 14 to the T-fitting 30 for disposal as desired.

In the embodiment of the invention shown in Fig. 1, which has been described, the buck 14 is swung to and from pressing position by hand, but if desired, the machine may include a small cylinder 31, Fig. 2, for swinging the buck unit. As shown in Fig. 2, the cylinder 31 is pivotally mounted at 32 on the main frame or pedestal 1 with its piston rod pivotally connected at 33 to the piston rod 8 of the main pressing cylinder and a valve or valves 34 for operation by the operator (preferably two valves constituting a two hand control) would be mounted on the guard rail 28 or in some other appropriate position, the arrangement being such that with the buck 14 in the loading position when the control valve or valves 34 is or are operated, compressed air would be admitted to the swinging cylinder 31 and move the unit into pressing position, power for pressing being supplied automatically by the valve 22 to the cylinder 6 in the manner already described with reference to Fig. 1. On the release arrangements being operated, not only will fluid pressure be exhausted from the main cylinder 6, but will also be exhausted from the swinging cylinder 31, and the buck 14 will be moved back into loading position by appropriate spring or pneumatic means. Where the buck unit is power swung, it is preferable to include in the machine a double acting dashpot or fluid check device 35 as an alternative for, or, as shown, in addition to the buffers or spring stops 16, 17 for the unit which have already been referred to in the description with reference to Fig. 1.

The valve devices incorporated in the machine may be of any suitable type. Conveniently, and as shown in Fig. 3, the automatically actuated valve 22 controlling the supply of compressed air to the power cylinder 6 is of the lift type, and is spring loaded. The spindle 36 of the valve 22 is adapted to be engaged by the piston rod 8 of the power applying cylinder of the buck unit immediately before such unit reaches the pressing position, the rod in the final portion of the movement

of the unit to such position forcing the valve 22 off its seat against the air pressure, and the reaction of the loading spring. Preferably the valve spindle 36 would be equipped with an anti-friction roller 37 adapted to be contacted by the piston rod 8.

Interposed between the pipe 19 leading from the source of supply of compressed air and the automatically actuated control valve 22 is the release valve means 23 under control of the operator. Conveniently, these means include a double acting spring loaded valve member normally closing communication between the automatic valve 22 via a port 38 and the atmosphere by way of a port 39 and the usual exhaust silencer 27, such double-acting valve member being adapted, when moved by the rod 26 operable by the release treadle or the equivalent, to release the press to open communication between the cylinder 6 and the atmosphere, and to close communication via a port 40, the port 38 and valve 22, between the source of supply of compressed air and the cylinder 6. It will be understood that air exhausting from the cylinder 6 will flow to the exhaust silencer 27 through the automatic valve 22 and the ports 38, 39 of the release valve in the order stated. After the power cylinder 6 has been exhausted, and before the release valve 23 is restored to normal, the movement of the buck unit towards the loading position will be commenced. The initial movement of the piston rod 8 away from its pressing position will permit the automatic valve 22 to close and cut off communication between the compressed air supply and the power cylinder 6, whereupon the release valve 23 may be allowed to return to normal and again open communication between the source of supply of compressed air and the automatic valve.

Unless the moving lower buck is equipped with steam heating means or with means for pulling or drawing air from the buck only a single movable or flexible pipe connection is required in the machine, this being the connection 20 for the compressed air from the automatic valve 22 to the cylinder 6, and to minimize the movement or flexing of this pipe, the latter is joined to the duct 21 leading to the cylinder as near as practicable to the pivotal axis of the cylinder and lower buck unit.

To obtain an arc of movement of the lower buck of the necessary length, the pivotal axis of the unit comprising the buck is disposed relatively close to the cylinder in the lower portion of the frame or pedestal of the machine as shown in Figs. 1 and 2.

The piston rod 8 constitutes a lever or sway beam, and, with the pivotal point disposed as stated, such lever has a longer and shorter arm. To compensate for the greater leverage in the longer arm carrying the buck 14, and it may be, carrying also the table 13, a suitable weight or weights 41 may be added if necessary to the cylinder, for example, to its lower cover. Conveniently, the cylinder cover 5 has upwardly extending side members or cheeks carrying the trunnions of the unit, and if desired, any additional counter-balancing requirements may be effected by means of weights associated with these cheeks.

As will be appreciated from the foregoing description the piston 9 of the lower cylinder 6 is required to effect only the small movement of the buck 14 necessary to bring the work into contact with the head 3 and to set up the requisite pressure, and thus has only a short stroke. Although

short, the stroke is such that the piston at all times will set up effective pressure on the work, notwithstanding compacting of the padding and clothing of the buck, or differences in the thickness of the work, so that mechanical means for adjusting the pressure between the buck and the head are not required.

What I claim is:

1. In a garment or like press, the combination of a main frame, a stationary ironing head mounted on said frame in a fixed location at the rear of the press, a movable unit pivotally mounted intermediate its ends in said frame to swing about a horizontal axis and having the portion above said pivotal axis of materially greater length than the portion below said axis, a buck comprised in and forming the upper end portion of said unit and movable through an arcuate path by swinging movements of said unit about its axis from a forward loading position clear of said head into a rearward pressing position beneath said head, and vice versa, a power applying cylinder for said buck effective to move it upwardly when it is in its pressing position, said cylinder being incorporated in the portion of said movable unit below the pivotal axis thereof and rendering the weight of such portion sufficient almost to counterbalance the upper portion of the unit including the buck, valve means automatically actuated as the buck reaches its pressing position to supply fluid under pressure to said power applying cylinder to cause upward pressure of the buck against the ironing head, and means for exhausting pressure fluid from said cylinder to release the press.

2. In a garment or like press, the combination of a main frame, a stationary ironing head mounted on said frame in a fixed location at the rear of the press, a movable unit pivotally mounted intermediate its ends in said frame to swing about a horizontal axis and having the portion above said pivotal axis of materially greater length than the portion below said axis,

a buck comprised in and forming the upper end portion of said unit and movable through an arcuate path by swinging movements of said unit about its axis from a forward loading position clear of said head into a rearward pressing position beneath said head, and vice versa, a power applying cylinder for said buck effective to move it upwardly when it is in its pressing position, said cylinder being incorporated in the portion of said movable unit below the pivotal axis thereof and rendering the weight of such portion sufficient almost to counterbalance the upper portion of the unit including the buck, cylinder and piston means for swinging the movable buck unit from its loading position into its pressing position, valve means operable by the press operator for controlling the supply of fluid under pressure to and its exhaust from said unit swinging cylinder, valve means automatically actuated as the buck reaches its pressing position to supply fluid under pressure to said power applying cylinder to cause upward pressure of the buck against the ironing head, and means for exhausting pressure fluid from said power applying cylinder to release the press.
